UNITED STATES PATENT OFFICE

2,580,330

THE ROD FOR CONCRETE WALL FORMS

Arthur H. Symons, Chicago, Ill., assignor to
Symons Clamp and Mfg. Company, Chicago, Ill.

Application December 4, 1948, Serial No. 63,537

1 Claim. (Cl. 25—131)

1

The present invention relates generally to tie rods for use in concrete construction. More particularly the invention relates to that type of tie rod which is designed for use with a pair of spaced apart vertically extending wall forms having oppositely disposed holes therein and attaching devices outwards of the holes, is adapted when in use to extend horizontally and have its ends project through the holes in the forms and attached to the attaching devices, serves, while in its operative position and in connection with pouring of concrete between the forms, to hold the forms against outward displacement, and is further adapted after hardening of the concrete, release of the attaching devices and removal or dismantlement of the forms, to have its projecting ends bent at substantially right angles and then turned or twisted in order to break or sever them from the central portion of the rod at points adjacent the side faces of the concrete wall.

In a wall form tie rod of this type it has heretofore been proposed to form on the central portion of the tie rod a pair of spaced apart so-called flats with curved or rounded outer and inner corners and, in addition, points of weakness outwards of the flats. The flats in connection with hardening of the concrete become interlocked with the concrete and serve to hold the central portion of the tie rod against rotation within the concrete wall while the ends of the tie rod are being twisted or turned. The points of weakness are ordinarily formed by splitting the tie rod outwards of the flats in order to weaken the tie rod in torsion but not in tension or by notching the tie rod so as to reduce its cross section at the desired break-off points. In practice it has been found that a wall form tie rod, having, in addition to a pair of spaced apart flats with curved or rounded outer and inner corners, points of weakness outwards of the flats for break-off purposes, is costly to manufacture because formation of the flats and the points of weakness necessitate the use of two separate sets of dies or complex dies.

The principal object of this invention is to provide a wall form tie rod which is materially less costly to produce than, and eliminates the objections of, previously designed tie rods and is characterized by the fact that it has only flats and the latter are located at the break-off points and have square outer corners which so reduce the cross sectional area of the tie rod at the points where they are formed that they weaken the tie rod and thus serve to provide the desired points of weakness in connection with turning

2

or twisting of the ends of the rod. By forming the flats on the tie rod so that the outer corners thereof are square as contradistinguished from curved or rounded the flats have a twofold purpose or function in that they not only prevent rotation of the central portion of the tie rod within the concrete during turning or twisting of the ends of the rod for break-off purposes but also provide the desired points of weakness where the ends of the rods break off.

It is also an object of the invention to provide a wall form tie rod which is generally an improvement in the art and not only effectively and efficiently fulfills its intended purpose but may be produced at an extremely low cost.

Other objects of the invention and the various advantages and characteristics of the present tie rod will be apparent from a consideration of the following detailed description.

20 The invention consists in the several novel features which are hereinafter set forth and are more particularly defined by the claim at the conclusion hereof.

In the drawing which accompanies and forms 25 a part of this specification or disclosure and in which like numeral or reference denote corresponding parts throughout the several views:

Figure 1 is a perspective view showing a tie rod embodying the invention in operative or connected relation with a pair of spaced apart vertically extending wall forms having oppositely disposed holes therein for receiving the ends of the tie rod and attaching devices outwards of the holes for connection to the outer projecting extremities of the tie rod;

Figure 2 is a perspective view showing the tie rod of Figure 1 after removal of the wall forms following hardening or solidification of the concrete, and illustrating in detail how the square corners at the outer ends of the flats form points of weakness whereby break-off of the ends of the tie rod occurs in connection with twisting or turning of the tie rod ends;

Figure 3 is an enlarged side elevation of one of the portions of the tie rod that have flats with the square outer corners, illustrating in detail the construction and design of the square corners at the outer ends of the flats;

Figure 4 is a plan view of the portion of the tie rod that is illustrated in Figure 3; and

Figure 5 is an enlarged vertical transverse section taken on the line 5—5 of Figure 2 and showing the manner in which the spaced apart flats on the central portion of the tie rod become interlocked with the wall after hardening of the

concrete and serve to hold the central portion of the tie rod against rotation within the wall.

The tie rod which is shown in the drawing constitutes the preferred form or embodiment of the invention. It is designed and adapted for use in connection with a pair of spaced apart vertically extending wall forms 6 and serves, as hereinafter described more in detail, to hold the forms against relative lateral displacement during pouring of concrete between the forms for purposes of forming a vertical wall. The forms 6 are of standard or conventional design and each, as shown in Figure 1, consists of a rectangular panel 7 and a rectangular reenforcing frame 8 on the outer side of the panel. The frames 8 of the forms 6 have horizontally extending intermediate crosspieces 9 and these are adapted to be positioned in horizontal alignment when the forms are in their operative or concrete wall forming position. Horizontal slots 10 are formed in the central portions of the panels 7 of the forms at points directly above the central portions of the horizontally extending crosspieces 9 of the reenforcing frames 8. When the tie rod is in its operative position with respect to the forms its ends project through the slots 10, as shown in Figure 1 of the drawing. The central portions of the frame crosspieces 9 are provided with attaching devices 11 for releasably locking the outer extremities of the tie rod to the forms in connection with use of the tie rod. As well understood in the art the forms 6 are arranged in an opposed laterally spaced upstanding position preparatory to pouring of concrete therebetween. In connection with positioning of the forms the ends of the tie rod are inserted through the slots 10 in the panels 7 of the forms. After insertion of the ends of the tie rod through the slots, the extremities of the tie rod are anchored to the forms by proper manipulation of the attaching devices 11. As soon as the attaching devices are connected to the extremities of the tie rod the tie rod serves to hold the forms 6 in proper position. Formation of a concrete wall is accomplished by pouring concrete between the two forms. As soon as the concrete hardens or solidifies the attaching devices 11 are released from the extremities of the tie rod and the forms are removed from the wall by shifting them outwards. After removal or dismantlement of the forms the projecting ends of the tie rod are twisted or turned in order to break or sever them from the central portion of the rod at points adjacent the side faces of the concrete wall.

The tie rod is formed of steel or any other suitable metal in order that it has the desired tensile strength. It is designated in the drawing by the reference numeral 12 and except for the parts heretofore described is circular in cross section and of uniform diameter or cross section throughout. The ends of the tie rod are bent into the form of flat, longitudinally elongated, horizontally extending loops 13 and these are adapted in connection with assembly of the forms 6 to be inserted through the slots 10 in the panels 7 and to fit flatly against the central portions of the upper surfaces of the crosspieces 9 of the reenforcing frames 8. The loops 13 are permanently closed by welding the doubled back extremities of the tie rod to the adjacent portions of the tie rod ends. On the central portion of the tie rod, i. e. the portion of the rod that is embedded in the concrete, two spaced apart, horizontally extending flats 14 are formed. These flats are formed by placing the central portion of the tie rod in a

punch press and subjecting it to the action of a pair of properly shaped coacting dies. The purpose of the flats 14 is to prevent rotation of the central portion of the tie rod in the concrete when the ends of the rod are twisted or turned for break-off purposes. As best shown in Figure 3 the top and bottom surfaces of the flats 14 are flat and parallel. The outer ends of the flats 14 join the immediately adjacent portions of the tie rod by way of corners 15 which are square as contradistinguished from curved or rounded. By having the outer corners of the flats square, the portions of the tie rod that are directly outwards of the outer ends of the flats are of less cross sectional area than the other portions of the tie rod and hence form points of weakness whereby in connection with twisting or turning of the projecting ends of the tie rod such ends are caused to fracture or break off at the square corners 15. As shown in Figure 3, the thickness of the flats 14 is approximately half the diameter of the rounded portions of the tie rod. The flats due, however, have substantially the same cross sectional area as the rounded portions of the rod. The dies which are used in forming the flats 14 are so designed or constructed that in connection with use thereof they shear or sever the portions of the rod that are directly outwards of the outer ends of the flats to a distance equal to approximately a quarter of the diameter of the round portions of the rod and hence form the square corners 15 at the outer ends of the flats. By providing the flats 14 with square outer corners 15 the flats have a twofold purpose or function in that they not only hold the central portion of the tie rod against turning in connection with twisting or turning of the ends of the rod, but also form directly outwards thereof points of weakness which, as hereinbefore pointed out, constitute the break-off points where the rod ends are fractured during twisting thereof. The inner ends of the flats 14 are the same as the outer ends and join the portions of the tie rod that are immediately inwards thereof by way of square inner corners 16. The flats 14 are positioned inwards of the loops 13 any desired distance, depending upon where it is desired to locate the points of weakness or break-off points. If it is desired to have the points of weakness inwards of the sides of the concrete wall the flats 14 are formed an appreciable distance inwards of the loops 13. If it is desired to have the points of weakness or break-off points directly adjacent the sides of the wall the flats are formed nearer the loops.

The attaching devices 11 for anchoring the projecting ends of the tie rod 12 to the wall forming forms 6 may be of any conventional or well known construction. They are illustrated in the drawing, however, as being like those of the wall form forming the subject matter of my copending United States patent application filed January 29, 1947 and serially numbered 724,999. As shown in the drawing, the devices 11 comprise U-shaped brackets 17, vertically extending wedge-shaped bolts 18 and horizontally extending wedges 19. The brackets 17 are arranged in straddled relation with the central portions of the horizontally extending crosspieces 9 of the reenforcing frames of the panels of the forms 6 and have longitudinally extending slots 20 in the central portions of the side legs thereof. The latter are aligned with vertically extending transversely disposed slots in the central portions of the frame crosspieces 9 and together with the last men-

tioned slots are adapted slidably to receive the vertically extending wedge shaped bolts 18. In assembling the forms 6 with respect to the tie rod 12 the forms are manipulated in such manner as to cause the loops 13 at the ends of the tie rod to be interposed between the slotted central portions of the crosspieces 9 of the reenforcing frames 8 and the slotted portions of the upper side legs of the brackets 17. After so manipulating the forms the vertically extending wedge shaped bolts 18 are driven downwards so that they extend through the slots in the upper side legs of the U-shaped brackets 17, the loops 13 on the projecting ends of the tie rod 12, the slots in the central portions of the crosspieces 9 and the slots in the central portions of the bottom side legs of the brackets. When the bolts 18 are driven fully downwards they serve to anchor the projecting ends of the tie rod to the forms to the end that the tie rod serves to prevent relative lateral displacement of the forms. The lower ends of the bolts 18 have longitudinally extending slots 21 for slidably receiving the horizontally extending wedges 19. The latter when driven through the slots 21 after proper positioning of the bolts 18 coact with the lower side legs of the brackets 17 to prevent upward displacement of the bolts 18 and thus releasably lock the bolts in their operative position. The attaching devices 11 are released from the projecting ends of the tie rod 12 after formation of the concrete wall between the forms 6 by first withdrawing the wedges 19 from the longitudinally extending slots 21 in the lower ends of the bolts 18 and then driving the bolts upwards until they are disengaged from the U-shaped brackets 17 and the loops 13. After removal of the form 6 from the concrete wall the wedge shaped bolts 18 may be inserted into the loops 13 and then turned in order to effect break-off of the projecting ends of the tie rods at the square corners 15 constituting the points of weakness or the break-off points on the tie rod 12. As an alternative, the projecting ends of the tie rod may be bent at right angles and then turned or twisted by any other suitable tool in order to effect the desired break-off at the square corners 15.

The herein described tie rod effectively and efficiently fulfills its intended purpose and is capable of being fabricated or produced at an extremely low cost. The latter is directly attributable to the fact that the rod embodies the flats 14 which, due to the fact that they have square outer corners 15, have a twofold purpose in that they prevent turning of the central portion of the tie

rod in connection with twisting of the ends of the rod and form the points of weakness or break-off points whereby the ends of the rod are severed in connection with twisting thereof after removal of the forms from the sides of the concrete wall.

Whereas the tie rod has been described as having loops 13 at its ends and being anchored to the forms by way of the attaching devices 11 it is to be understood that the projecting ends of the tie rod may be differently shaped or formed and connected to the forms in any other manner. It is also to be understood that the invention is not to be restricted to the details set forth since these may be modified within the scope of the appended claim without departing from the spirit and scope of the invention.

Having thus described the invention what I claim as new and desire to secure by Letters Patent is:

As a new article of manufacture, a tie rod designed to hold in spaced apart relation a pair of upstanding concrete wall forms, formed originally of a one-piece length of metal of circular cross section and uniform diameter from end to end, consisting of uniformly cylindrical central and end parts, adapted to have its central part and the inner portions of the end parts thereof embedded directly in the concrete that is poured between the forms, and having between its central and end parts a pair of die formed parallel sided flats which are of rectangular cross section, are of uniform thickness from end to end but of less thickness than said central and end parts, and have square or right angle corners between their outer ends and the contiguous portions of the end parts, the points of juncture between the outer ends of the flats and said contiguous portions being of less cross sectional area than the end parts due to said square or right angle corners and forming points of weakness or break-off points whereby said end parts in connection with turning thereof relatively to the central part of the rod after pouring of concrete between the forms are caused to be severed at only said square corners.

ARTHUR H. SYMONS.
